(57) **CLAIM**

We claim the ornamental design for a vehicle body front, as shown and described.

DESCRIPTION

FIG. 1 is a perspective view of a vehicle body front showing our new design;

FIG. 2 is a left side elevational view thereof, the right side view being a mirror image not shown;

FIG. 3 is a top plan view thereof;

FIG. 4 is a bottom plan view thereof;

FIG. 5 is a rear elevational view thereof; and,

FIG. 6 is a front elevational view thereof.
